WHEELED GUN CARRIAGE

Nicolas Emilién Methlin, Paris, France, assignor
to Schneider & Cie, Paris, France, a company
of France

Application June 30, 1932, Serial No. 620,272
In France September 7, 1931

27 Claims. (Cl. 89—40)

The present invention relates to a wheeled gun carriage with split trail and one or more auxiliary trails as well as detachable wheels or an oscillating or non-oscillating set of wheels for rapid conversion into an anti-aircraft gun-carriage.

The gun carriage according to the invention is characterized by a system of trail legs so adapted that the said trail legs may both be brought simultaneously, either by individual or coupled action, alternatively into a position with the head raised in which the system of the said trail legs is arranged for travelling or for normal firing on wheels, or into a position with the head lowered in which the oscillating gun and cradle, during the pivoting of the top carriage, can pass above the system of trail legs for firing at aerial objectives.

In order to be able to effect the change-over of the trail legs from the position with the head raised into the position with the head lowered according to the invention, a construction may be provided in which the trail legs are acted upon individually, or both trail legs are acted upon together, the latter being adapted to turn or slide separately or conjointly in the pintle bearing or carriage body when the carriage comprises an oscillating axle. When the carriage does not comprise an oscillating axle, the legs of the split trail being in this case pivoted to a cross-piece adapted to oscillate in the pintle bearing rigidly supported by the axle, the change-over from the raised position to the lowered position may also be effected by pivoting the system of trail legs about the pivot joining the cross-piece to the carriage body, or a cross-piece in two parts may be employed which parts are adapted to occupy two positions, one in which they raise the heads of the trail legs pivoted to their free ends and the other in which they lower them. Finally, particularly in the case in which the carriage is not provided with an oscillating axle, the change-over from the raised position to the lowered position may be effected by a displacement of the longitudinal joint of the system of trail legs in the pintle bearing, or there may be provided for the longitudinal joint of the system of trail legs a movable bearing adapted to be brought alternatively into an upper position or into a lower position, for example by means of a screw and nut mechanism. These various constructional forms which are merely cited by way of example are represented in the accompanying drawings.

Figures 1 and 2 show respectively in side elevation and plan a constructional form of the inven-

tion employed in combination with equipment on wheels comprising an oscillating axle.

Figure 3 is an elevation view of a portion of the embodiment of Figures 1 and 2 showing the trail in lowered position.

Figure 4 is a fragmentary elevation showing the connection between the auxiliary trail and the main trail.

Figure 5 is a fragmentary plan view showing the auxiliary trail connected to the main trail.

Figure 6 is a fragmentary elevation corresponding to Figure 5 and showing the hooks of the main trail which are adapted to be engaged by the auxiliary trail.

Figure 7 is a plan view in section taken substantially on line 7—7 of Figure 3.

Figure 8 is an end elevation of the trail leg head and the intermediate piece of the embodiment of Figures 1, 2 and 3.

Figures 9 and 9a are fragmentary elevations showing a modified manner of connecting a trail leg to the pintle bearing in raised and lowered positions.

Figure 10 is an elevation of a portion of a gun mount showing still another embodiment of the invention.

Figure 10a is a horizontal sectional view taken substantially on line 10a—10a of Figure 10.

Figure 10b is a fragmentary elevation of a modification of the device shown in Figures 10 and 10a.

Figure 11 is an elevation part in section of a portion of a gun mount showing still another embodiment of the invention.

Figure 12 is a plan view corresponding to Figure 11.

Figure 13 is a side elevation corresponding to Figure 11, but including a showing of the trail leg foot.

Figure 14 is an end view part in section of the trail cross piece.

Figures 15 and 16 are an end elevation and a plan view, respectively, part in section, of the device for coupling the detachable wheels to the pintle bearing.

Figure 17 is an elevation of a portion of a gun mount showing still another embodiment of the invention.

Figures 18, 19 and 20 are end elevations and a plan view, all partly in section, of the embodiment of Figure 17, Figure 18 showing the trail legs in lowered position and Figure 20 showing them in raised position.

Figures 21 and 22 are fragmentary elevation and plan views, respectively, partly in section,

of still another modification of the present invention.

Figures 23 and 24 are side elevation and plan views of a portion of another gun mount embodying another form of the invention.

Figure 25 is a sectional end elevation taken substantially on line 25-25 of Figure 24.

Figures 26 and 27 are partial elevation and plan views of another embodiment of the invention.

Figure 28 is an end elevation in section through the trail legs of the embodiment of Figure 26.

Figure 29 is a part elevation corresponding to Figure 26 but showing the auxiliary trail in raised position.

The equipment itself may be of any known construction. It may comprise for example an oscillating mass, gun 1 adapted to recoil on a cradle 2, the latter being adapted to oscillate by means of trunnions 3 in a top carriage $a-a^1$ for elevation, the said top carriage in turn being adapted to pivot in a carriage body or a pintle bearing b , a longitudinal joint c^2 permitting a transverse oscillation of the set of wheels c^1-c-c^1 relatively to an intermediate piece c^3 carried by the pintle bearing b , due to an attachment b^1 by means whereof the entire set of wheels may be detached from the pintle bearing by horizontal sliding. The bottom carriage comprises two trail legs d , d , which for the purpose of being spread out and brought together are movable about pivots e , e which in the known equipments are formed on or carried by the pintle bearing b .

According to the invention, the pivots e are each carried on an intermediate piece f which is adapted to turn about a pivot b^2 which is slightly inclined to the horizontal, thereby permitting each of the trail legs to take up two positions which are symmetrical relatively to the said pivot. One of these positions is shown in full lines in Figure 3, while the other shown in chain line corresponds to the position for firing on wheels and for travelling.

The pivot b^2 , as shown in Figure 3, will be given an inclination such that its geometrical axis passes in the immediate vicinity of the foot g of the trail leg. With this constructional form, it is necessary to be able to turn the foot of the trail leg which is intended to receive a sliding trail spade and to provide for this purpose a pivot g^1 between this trail leg foot and the trail leg body d , the geometrical axis of the pivot g^1 being situated in the extension of the geometrical axis of b^2 . Under these conditions, the trail legs d can be turned about their pivot b^2 joining them to the carriage body without this operation involving any displacement of the carriage body or of the foot of the trail leg.

In the example shown, the equipment comprises a detachable auxiliary trail h , in one or more parts, which is adapted to be fixed to the pintle bearing b for example by means of pins i , and at the same time to be connected to the trail legs d when the latter are in their lowered position. For this purpose, the auxiliary trail may comprise a hook h^1 , as shown in elevation in Figures 1 and 4, and in part plan in Figure 5. When the legs of the split trail are in their desired spread-out position for battery position for firing against aerial objectives, the said hook engages corresponding hooks d^1 carried by the heads of the said trail legs d . With the equipment which has just been described, the legs d of the split trail may be brought together into the position with raised head for travelling, as shown in chain

lines at I in Figure 2. Of course, for travelling, the auxiliary trail will have to be removed and transported separately. In case of surprise, firing may be carried out with the trail legs brought together in the positions I and anchored to the ground.

By leaving the trail legs in the raised position shown in Figure 1, firing may be effected with the trail legs spread apart in a position of spread only limited by the wheels. Such a position II is shown in full lines in Figures 1 and 2. Finally, in order to convert the equipment with a view to firing against aerial objectives, the heads of the trail legs are brought into the lower position by rotation and the trail legs may then be spread further apart (position III).

In order to convert the equipment definitely for firing against aerial objectives, an auxiliary trail h will be placed in position and the set of wheels will then be removed. As shown in chain lines in Figure 1, the oscillating gun and cradle in all positions of elevation can pass above the trails, the pivoting of the gun and cradle in the pintle bearing b and the recoil of the gun on the cradle being possible throughout the whole field of fire of 360°.

In the example just described, the hooking of each intermediate piece on the pivot b^2 integral with the pintle bearing b may be effected in any appropriate manner. One constructional form is shown in Figures 3, 7 and 8.

As will be seen, the intermediate piece is made in two parts f^1 and f^2 engaging the pivot b^2 .

The lower part f^1 carries the pivot e around which the trail leg body d is adapted to turn. The trail leg head d^4 is adapted to engage a lug f^3 of the intermediate piece in two positions of angular displacement, for example by means of a pin d^5 .

In order to bring the trail legs from the raised position to the lowered position, a simple attaching device may be provided. Each of the intermediate pieces, instead of being constructed as in example shown in Figures 3, 7 and 8, in box shape, will be made in the form of a slide block having in cross-section the same profile as that of the head shown in Figure 3 and which will engage a guide of corresponding profile formed on the pintle bearing b and replacing the pivot b^2 in Figure 3. This modification is shown in Figures 9 and 9a.

In these figures, f denotes the intermediate piece which makes a sliding fit on a guide b^3 in the form of a projection on the pintle bearing b .

In Figure 9 the trail leg occupies the bottom position in which it is locked by a locking member, such as a cotter d^6 . In order to bring the trail leg into the top position, the member b^6 will be withdrawn, the intermediate piece will be disengaged from the guide b^3 and the trail leg will be turned through 180°. It can then be fitted again on the guide b^3 when it will occupy a position suitable for travelling or firing on wheels. This position is shown in Figure 9a.

In the embodiment of Figures 10 and 10a, for each of the heads the pintle bearing carries a guide b^3 , the section of which is clearly visible in Figure 10a and on which the corresponding trail leg head is engaged. The fixing of the trail legs in the bottom position is shown in full lines in Figure 10. By withdrawing the pin d^8 , the trail leg may be raised from the lowered position into the position for travelling or firing on wheels, the trail leg then being fixed by means of pin d^8 engaging a second hole situated at a suitable

level on the pintle bearing as indicated in chain lines in Figure 10. In Figure 10a, only one of the intermediate pieces has been shown. The figure shows, however, the guides for the intermediate pieces of the two legs of the split trail.

In the example shown in Figure 10b, the guide provided for each of the trail-leg heads on the pintle bearing b is in the form of a rack b^4 for a pinion or a worm d^9 journalled in the trail leg head and adapted to be manipulated by a hand wheel or ratchet.

In both embodiments of Figures 10, 10a and 10b, the centers of curvature of the arcuate guides b^3 or racks b^4 are substantially coincidental with the points of engagement of the trail-leg feet g with the ground.

In the example shown in Figures 11 to 16, the legs d of the split trail are each pivoted on a pin e carried by a cross-piece e^1 integral with a pivot k movable in a bearing formed in the pintle bearing b .

The trail-leg feet are joined to the trail-legs d by pivots g^1 permitting the trail-leg feet to be righted, whether the trail-leg is in the top position or the bottom position. According to the invention, by rotating the cross-piece e round the pivot k , these arrangements permit the trail-legs to be brought from the top position, shown in chain lines, to the bottom position shown in full lines in Figure 13. In the travelling position, and during the above-mentioned rotation, the trail-legs are brought together according to arrangement I in Figure 12.

The trail-legs may be placed in the top position or in the bottom position equally in each of the positions II and III in Figure 12. However, for the purpose of this change which is effected by rotation of the cross-piece, it is essential to bring the trail-legs together in the position I. It should be noted that during this change-over from the top position into the bottom position, the right-hand trail-leg passes to the left and vice versa.

The inclination of the pivot k has the result of preserving the verticality of the pintle bearing b in each of these two positions.

The pivots g^1 are so arranged that their axes bisect the two positions of the trail-leg, thus maintaining the feet g of the trail-legs substantially vertical.

The system of trail-legs having been lowered, the legs may be spread apart into the position III for firing against aerial objectives, the auxiliary trail h having been put in position as in the example shown in Figures 1 to 3. The set of wheels can then be removed by disengaging the bolts m (Figure 16) which permits the brackets c' projecting from the axle c to be disengaged in their turn and the set of wheels to be removed. In the example just described, the auxiliary trail h is fixed to the pintle bearing b by a pin h^2 , while the forks h^3 of the head of trail h are fixed by a pin h^4 to bosses d^7 formed on the trail-leg heads d . A device for locking the trail-legs in their top position may also be provided by engagement between the bosses or lugs d^7 on the trail-legs and corresponding lugs provided on the pintle bearing.

Figures 17 to 20 show a modification of a similar application of the invention, that is to say, in the case in which the system of trail-legs is pivoted by a pivot k , as in the example shown in Figures 11 to 16, to the pintle bearing, the carriage not having an oscillating axle. In this example, the cross-piece e^1 carrying the vertical

pivot e of the trail-legs for their angular displacement, is made in two elements e^2 and e^3 which are hinged about the pivot k of the system of trail-legs, the pivot being rigidly integral with the pintle bearing b . One of the elements e^3 is in the form of a forked lever and carries the pivot e of one of the trail-legs, while the other element e^2 which carries the pivot e of the other trail-leg is adapted to swing between the forks e^3 . Thus, this two-part cross-piece is adapted to occupy two positions, one of which is shown in the side and end elevations of Figures 17, 18 and 19, while the other is shown in the end elevation of Figure 20.

Figures 21 and 22 show another modification which may be employed in combination with a carriage having an oscillating axle. In this example, each of the trail-legs d is jointed both to the trail-leg foot g by a pivot g^1 and by a pivot d^9 to a bush e^6 carried by a vertical pivot e^1 journalled in the pintle bearing b . The pivots g^1 and d^9 have the same geometrical axis, the trail-legs being adapted to be locked in the top position shown in chain lines in Figure 21 by a bolt which at the same time engages a lug e^7 provided on the pivot e and a lug d^{10} carried by the trail-leg. In the bottom position the lug d^{10} serves for the attachment of the auxiliary trail h .

In the example shown in Figures 23 to 25, the pintle bearing b comprises, for each of the heads of the legs d of the split trail, a helical guide b^3 which may be formed as a projection on the body of the pintle bearing b as shown in Figure 24 and which is engaged by the corresponding trail-leg head. In the case in which the trail-leg body d is rigidly integral with the head engaging the guide, the trail-legs are capable of assuming exactly two positions, as indicated in full lines and chain lines respectively in Figures 23 and 24. When the trail-legs occupy the upper position at the top of the guides b^3 , they will necessarily be together for the purpose of limbering up and transport. When the trail-legs occupy the bottom position indicated in full lines, they will necessarily be at the desired spread for the battery position of the equipment, with wheels removed, for firing against aerial objectives, or with a view to firing on the oscillating axle for ordinary field firing. Of course, it is possible in addition to provide heads of split trail-legs guided helically on the pintle bearing b , the trail-leg bodies being hinged to the said heads by vertical pivots. In this case, it would be possible to give any desired positions of spread to the trail-legs.

The equipment may comprise, as shown in Figures 23 and 24, an auxiliary trail h , the head of which will be guided on segments b^5 provided on the pintle bearing b . Thus, by sliding the head on the guide, this trail may be brought into the travelling position shown in chain lines in Figure 23, in which the trail body will be hooked underneath the cradle by a link $2'$. In the bottom position, the trail h may be fastened to the trail-legs d , the latter carrying for this purpose, like the trail h , lugs (d^7 and h^3 , respectively) through which are passed pins.

Figures 26 to 29 show a constructional form applied in combination with a carriage not provided with oscillating axle, that is to say, a carriage in which the legs of the split trail are pivoted to a cross-piece adapted to oscillate by means of a longitudinal pivot in the pintle bearing. In this example, the change-over from the bottom position of the trail-leg head to the top

position is obtained by a vertical displacement of the longitudinal pivot of the cross-piece. This pivot, in the form shown in Figures 26 to 29 is displaced vertically by the displacement of its bearing which is adapted to slide on or in a guide carried by the pintle bearing.

In Figures 26 to 28, the trail legs are shown in the bottom position, while in Figure 29 they are shown in the top position.

- 10 10 As shown in the figures, the pivot *k* of the cross-piece *e*¹ to which the legs *d* of the split trail are hinged around vertical hinge pins *e* is movable in a bearing *K* formed by a half collar, having its arms guided on guides *B* formed on the 15 pintle bearing. The vertical displacement of the half-collar *K* may be effected for example by unrolling on the racks *B*¹ formed on the pintle bearing *b*, the pinions *K*¹ journalled in the arms of the half collar *K*. The carriage will comprise 20 an auxiliary trail *h* having its fork-shaped head pivoted on trunnions *K*² provided on the branches of the half-collar bearing *K*. By means of pins *h*² the auxiliary trail may be attached to the bearing *K* either in the bottom position (Figures 25 25 and 27) or in the top position (Figure 29).

The same system of vertical movement may be employed with an oscillating axle, in which case the pivots *e* will be carried directly by the half collar *K*.

30 I claim:

1. In a gun carriage, a pintle bearing, an oscillating gun and cradle pivotally mounted on said bearing, transportation means detachably connected to said bearing, a split trail for said carriage secured to said bearing, means for raising, lowering and spreading the legs of said trail relative to said bearing, said means being so constructed and arranged that said trail may be quickly moved, without affecting or interfering 40 with the position and operation of the oscillating gun and cradle, from a normal raised position for firing with said transportation means in place to a lowered emplaced position with the transportation means removed, an auxiliary trail, and means for securing said auxiliary trail to a portion of the gun carriage that is fixed during firing when said split trail is in lowered emplaced position, said split and auxiliary trails being so located when in emplaced position that the oscillating gun and cradle may pivot thereabove for firing at aerial objectives at any azimuth.

2. In a gun carriage, a pintle bearing, an oscillating gun and cradle pivotally mounted on said bearing, transportation means detachably connected to said bearing, a split trail for said carriage secured to said bearing, means for shifting the legs of said trail vertically with respect to said bearing, and without changing the position 55 of the oscillating gun and cradle relative to the ground, from a normal raised position for firing with said transportation means in place to a lowered emplaced position with the transportation means removed, an auxiliary trail, and means for securing said auxiliary trail to a portion of the gun carriage that is fixed during firing when said split trail is in lowered emplaced position, said split and auxiliary trails being so located when in emplaced position that the oscillating gun and cradle may pivot thereabove for firing at aerial objectives at any azimuth.
3. In a gun carriage, a pintle bearing, an oscillating gun and cradle pivotally mounted on said bearing, transportation means detachably connected to said bearing, a split trail for said

carriage secured to said bearing and having a plurality of legs, each of said legs having a head adjacent said bearing and a foot adapted to engage the ground, means for raising and lowering said trail leg heads relative to said bearing without affecting the position of the oscillating gun and cradle relative to the ground, an auxiliary trail, and means for securing said auxiliary trail to a portion of the gun carriage that is fixed during firing when said trail leg heads are in lowered position, said split and auxiliary trails being so located when in said lowered position that the oscillating gun and cradle may pivot thereabove for firing at aerial objectives at any azimuth.

4. In a gun carriage, a pintle bearing, an oscillating gun and cradle pivotally mounted on said bearing, transportation means detachably connected to said bearing, a split trail for said carriage secured to said bearing and having a plurality of legs, each of said legs having a head adjacent said bearing and a foot adapted to engage the ground, means for raising and lowering said trail leg heads relative to said bearing without affecting the position of the oscillating gun and cradle relative to the ground, and a pivotal connection between each of said trail feet and its associated trail leg, whereby said feet may be maintained in the same position regardless of the positions of said trail heads and legs.

5. In a gun carriage, a pintle bearing, an oscillating gun and cradle pivotally mounted on said bearing, transportation means detachably connected to said bearing, a split trail for said carriage secured to said bearing, means for raising, lowering and spreading the legs of said trail relative to said bearing, an auxiliary trail, and means for securing said auxiliary trail to said split trail legs when the latter are in lowered position.

6. In a gun carriage, a pintle bearing, an oscillating gun and cradle pivotally mounted on said bearing, transportation means detachably connected to said bearing, a split trail for said carriage secured to said bearing, means for raising, lowering and spreading the legs of said trail relative to said bearing, an auxiliary trail, and means for securing said auxiliary trail both to said bearing and to said split trail legs when the latter are in lowered position.

7. In a gun carriage, a pintle bearing, an oscillating gun and cradle pivotally mounted on said bearing, transportation means detachably connected to said bearing, a split trail for said carriage secured to said bearing and having a plurality of legs, each of said legs having a head adjacent said bearing and a foot adapted to engage the ground, means for raising and lowering said trail leg heads relative to said bearing without affecting the position of the oscillating gun and cradle relative to the ground, an auxiliary trail, and means for securing said auxiliary trail to said trail leg heads when the latter are in lowered position.

8. In a gun carriage, a pintle bearing, a trail leg having a head adapted to be secured to said bearing, means for securing said trail leg head to said bearing in both raised and lowered positions and for shifting from one of said positions to the other without affecting the position of said bearing relative to the ground, an auxiliary trail, and means for securing said auxiliary trail to a portion of the gun carriage that is fixed during firing when said trail leg head is in lowered position.

9. In a gun carriage, a pintle bearing, a trail leg having a head adapted to be secured to said bearing, means for securing said trail leg head to said bearing for pivotal movement relative thereto about an axis slightly inclined to the horizontal, whereby said trail leg may be quickly moved, without affecting the position of said bearing relative to the ground, from a normal raised position for firing with the gun transportation means in place to a lowered emplaced position with said transportation means removed for firing at aerial objectives, and means for mounting said trail leg for pivotal movement about an axis substantially at right angles to said first named axis.
10. In a gun carriage, a pintle bearing, a trail leg having a head adapted to be secured to said bearing and a foot adapted to engage the ground, means for securing said trail leg head to said bearing for pivotal movement relative thereto about an axis slightly inclined to the horizontal whereby said trail leg may be moved from raised to lowered position without affecting the position of said bearing relative to the ground, and means for securing said trail leg foot to said trail leg for pivotal movement about an axis substantially coaxial with said first named axis.
11. In a gun carriage, a pintle bearing, a trail leg having a head adapted to be secured to said bearing and a foot adapted to engage the ground, means for securing said trail leg head to said bearing for pivotal movement relative thereto about an axis slightly inclined to the horizontal, whereby said trail leg may be moved from raised to lowered position without affecting the position of said bearing relative to the ground, means for mounting said trail leg for pivotal movement about an axis substantially at right angles to said first named axis, and means for securing said trail leg foot to said trail leg for pivotal movement about an axis substantially coaxial with said first named axis.
12. In a gun carriage, a pintle bearing, a trail leg adapted to be secured to said bearing, and means for securing said trail leg to said bearing in a plurality of different positions relative to said bearing including a pivot lug formed on said bearing, an intermediate member engaging said lug and adapted to pivot therearound, and a pivotal connection between said intermediate member and said trail leg, the axes about which said pivotal movements take place being substantially perpendicular to one another.
13. In a gun carriage, a pintle bearing, a trail leg adapted to be secured to said bearing, and means for securing said trail leg to said bearing in a plurality of different positions relative to said bearing including a pivot lug formed on said bearing, an intermediate member engaging said lug and adapted to pivot therearound, the axis of said pivotal movement being inclined slightly from the horizontal, and a pivotal connection between said intermediate member and said trail leg having an axis substantially perpendicular to said first named axis.
14. In a gun carriage, a pintle bearing, a trail leg adapted to be secured to said bearing, and means for securing said trail leg to said bearing in a plurality of different positions relative to said bearing including a pivot lug formed on said bearing, an intermediate member engaging said lug and adapted to pivot therearound, a pivotal connection between said intermediate member and said trail leg, a ground engaging foot for said trail leg, and a pivotal connection between said
- foot and said leg having an axis substantially coaxial with that of said pivot lug.
15. In a gun carriage, a pintle bearing, a trail leg adapted to be secured to said bearing, and means for securing said trail leg to said bearing in a plurality of different positions relative to said bearing including a pivot lug formed on said bearing, an intermediate member engaging said lug and adapted to pivot therearound, the axis of said pivotal movement being inclined slightly from the horizontal, a pivotal connection between said intermediate member and said trail leg having an axis substantially perpendicular to said first named axis, a ground engaging foot for said trail leg, and a pivotal connection between said foot and said leg having an axis substantially coaxial with said first named axis.
16. In a gun carriage, a pintle bearing, a split trail having a plurality of legs each adapted to be secured to said bearing, means for securing each of said trail legs to said bearing in raised and lowered positions for normal and aerial firing, respectively, an auxiliary trail, hook members formed on the inner ends of said trail legs, and a cooperating hook member carried by said auxiliary trail and adapted to engage the hook members of said trail legs when the latter are in lowered position.
17. In a gun carriage, a pintle bearing, a split trail having a plurality of legs each adapted to be secured to said bearing, means for securing each of said trail legs to said bearing in raised and lowered positions for normal and aerial firing, respectively, including a pivot lug formed on said bearing, an intermediate member engaging said lug and adapted to pivot therearound on an axis slightly inclined to the horizontal, and a pivotal connection between said intermediate member and said trail legs having an axis substantially perpendicular to said first named axis, an auxiliary trail, hook members formed on the inner ends of said trail legs, and a cooperating hook member carried by said auxiliary trail and adapted to engage the hook members of said trail legs when the latter are in lowered position.
18. In a gun carriage, a pintle bearing, a split trail having a plurality of legs adapted to be secured to said bearing, and means for securing said trail legs to said bearing in raised and lowered positions for normal and aerial firing, respectively, including a cross-piece connected to said bearing for pivotal movement about an axis slightly inclined to the horizontal, and pivotal connections between said cross-piece and said trail legs having axes substantially perpendicular to said first named axis.
19. In a gun carriage, a pintle bearing, a split trail having a plurality of legs adapted to be secured to said bearing, and means for securing said trail legs to said bearing in raised and lowered positions for normal and aerial firing, respectively, including a cross-piece connected to said bearing for pivotal movement about an axis slightly inclined to the horizontal, pivotal connections between said cross-piece and said trail legs having axes substantially perpendicular to said first named axis, ground engaging feet for said trail legs, and a pivotal connection between each of said feet and its associated trail leg.
20. In a gun carriage, a pintle bearing, a split trail having a plurality of legs adapted to be secured to said bearing, and means for securing said trail legs to said bearing in raised and lowered positions for normal and aerial firing, respectively, including a cross-piece connected to

- 5 said bearing for pivotal movement about an axis slightly inclined to the horizontal, pivotal connections between said cross-piece and said trail legs having axes substantially perpendicular to said first named axis, ground engaging feet for said trail legs, and a pivotal connection between each of said feet and its associated trail leg having an axis substantially coaxial with said first named axis.
- 10 21. In a gun carriage, a pintle bearing, a split trail having a plurality of legs adapted to be secured to said bearing, and means for securing said trail legs to said bearing in raised and lowered positions for normal and aerial firing, respectively, including a cross-piece pivotally connected to said bearing, pivotal connections between said cross-piece and said trail legs, an auxiliary trail, and means for securing said auxiliary trail to both said bearing and said trail legs when the latter are in lowered position.
- 15 22. In a gun carriage, a pintle bearing, a split trail having a plurality of legs adapted to be secured to said bearing, and means for securing said trail legs to said bearing in raised and lowered positions for normal and aerial firing, respectively, including a cross-piece connected to said bearing for pivotal movement about an axis slightly inclined to the horizontal, pivotal connections between said cross-piece and said trail legs having axes substantially perpendicular to said first named axis, ground engaging feet for said trail legs, a pivotal connection between each of said feet and its associated trail legs having an axis substantially coaxial with said first named axis, an auxiliary trail, and means for securing said auxiliary trail to both said bearing and said trail legs when the latter are in lowered position.
- 20 23. In a gun carriage, a pintle bearing, a split trail having a pair of legs adapted to be secured to said bearing, and means for securing said trail legs to said bearing in raised and lowered positions for normal and aerial firing including a slide guide carried by said bearing, an intermediate member engaging said guide and adapted to slide therealong, a cross-piece pivotally connected to said intermediate member, and pivotal connections between said cross-piece and said trail legs.
- 25 24. In a gun carriage, a pintle bearing, a split trail having a pair of legs adapted to be secured to said bearing, and means for securing said trail legs to said bearing in raised and lowered positions for normal and aerial firing, including a pair of substantially vertical slide guides carried on opposite sides of said bearing, a collar member having slide blocks adapted to engage said guides and to slide up and down therealong, a cross-piece pivotally connected to said collar member, and pivotal connections between said cross-piece and said trail legs.
- 30 25. In a gun carriage, a pintle bearing, a split trail having a pair of legs adapted to be secured to said bearing, and means for securing said trail legs to said bearing in raised and lowered positions for normal and aerial firing, respectively, including a pair of substantially vertical slide guides carried on opposite sides of said bearing, a collar member having slide blocks adapted to engage said guides and to slide up and down therealong, a cross-piece having a substantially horizontal pivot pin journaled in said collar member, and pivotal connections having substantially vertical axes between said cross-piece and said trail legs.
- 35 26. In a gun carriage, a pintle bearing, a split trail having a pair of legs adapted to be secured to said bearing, and means for securing said trail legs to said bearing in raised and lowered positions for normal and aerial firing, respectively, including a pair of substantially vertical slide guides carried on opposite sides of said bearing and each provided with teeth constituting a rack, a collar member adapted to engage said guides and carrying a pair of pinions adapted to roll up and down along said racks, a cross-piece pivotally connected to said collar member, and pivotal connections between said cross-piece and said trail legs.
- 40 27. In a gun carriage, a pintle bearing, a split trail having a pair of legs adapted to be secured to said bearing, and means for securing said trail legs to said bearing in raised and lowered positions for normal and aerial firing, respectively, including a slide guide carried by said bearing, an intermediate member engaging said guide and adapted to slide therealong, a cross-piece pivotally connected to said intermediate member, pivotal connections between said cross-piece and said trail legs, an auxiliary trail trunnioned on said intermediate member, and means for securing said auxiliary trail to said member in either raised or lowered position.

NICOLAS EMILIEN METHLIN.
